STRAND FORMING APPARATUS

Waldemar C. Ewaldson, Millington, N. J., assignor
to Western Electric Company, Incorporated,
New York, N. Y., a corporation of New York

Application March 15, 1945, Serial No. 582,970

9 Claims. (Cl. 28—1)

1

This invention relates to strand forming apparatus, and more particularly to apparatus for forming switchboard cables.

In the manufacture of switchboard equipment, it has been found advantageous to provide the cables, with their groups of electrical conductors which are to complete the necessary electrical connections with the various electrical units, to be substantially flat and with given dimensions so that they may be easily positioned in the switchboard structures consuming a minimum of space therein.

An object of the invention is to provide a strand forming apparatus which is simple in structure and highly efficient in compressing strands into predetermined cross sectional contours of given thicknesses.

With this and other objects in view, the invention comprises a strand forming apparatus particularly adapted for forming cables and including a rotatable roller with a fixed axis, cooperating with a companion roller, the latter being mounted on a movable axis, parallel to the fixed axis and under a predetermined variable pressure to compress a strand into a given cross sectional contour during the advancement of the strand.

Other objects and advantages will be apparent from the following detailed description when considered in conjunction with the accompanying drawings, wherein

Fig. 1 is a front elevational view of one species of the invention;

Fig. 2 is a front elevational view of the structure shown in Fig. 1, portions thereof being broken away while others are shown in section;

Fig. 3 is an enlarged fragmentary front elevational view of the dial and pointer of the structure shown in Fig. 1;

Fig. 4 is a fragmentary sectional view of another species of the invention; and

Fig. 5 is a fragmentary sectional view taken along the lines 5—5 of Fig. 4.

Referring now to the drawings, attention is first directed to Figs. 1 to 3 inclusive. The species of the invention shown in these figures includes a frame composed of a base 10 and vertical sides 11 mounted thereon, the upper ends of the sides being closed by a cover 12. A roller 14, having end members 15 integral therewith, is mounted upon a shaft 16, the ends of which are supported by bearings 17, the latter being supported as illustrated in Fig. 2 in apertures in the sides 11. A companion roller 20, positioned to interengage the roller 14 by extending between the end members 15, is rotatably mounted upon a shaft 21,

2

the ends of the latter being supported in parallel members 22 of a lever 23. The shaft 21 is fixed in position by a set screw 24. The lever 23 is pivotally mounted upon a shaft 26, the outer ends of which are mounted in apertures in the sides 11.

An upwardly projecting arm 27 of the lever 23 supports a cam block 28 which is positioned to ride upon the periphery of a cam 30. The cam 30 is mounted upon a shaft 31 and has a peripheral contour as illustrated in Fig. 1 with the peripheral surface thereof beginning at a low portion 32, and having a constant rise to its highest portion 33. The shaft 31 is journaled in suitable bearings 34 in the sides 11, and has a dial 35 fixedly mounted upon the forward end thereof. The dial 35 is divided adjacent its periphery by graduations 36 which are to indicate one hundredths of an inch the thickness to which the strand or material is to be reduced while passing between the rollers 14 and 20. The graduations 36 are therefore spaced proportionately to the varying contour of the cam 30 so that, by positioning a given graduation adjacent a pointer 38, it will be known that a given portion of the cam surface 30 will be adjacent the cam block 28 to locate the roller 20 a selected measured distance from the roller 14. The dial 35 is provided with a handle 39, by the aid of which it may be manually rotated in either direction relative to the pointer 38. The pointer 38 is mounted upon a housing 40 which is a part of the cover 12. The housing 40 includes a plunger 41 positioned to engage the back of the dial 35 and apply a predetermined braking or holding force to the dial through the aid of a spring 42. The spring 42 is disposed in the housing and in the hollow end of the plunger 41. Its force may be varied through the actuation of an adjusting screw 43 threadedly disposed in a nut 44 which closes the end of the housing 40.

Pressure means is provided to normally hold the roller 20 the selected measured distance from the roller 14. This means includes a spring 46 which rests upon a member 47, the latter being disposed upon the free end of the lever 23 and connected thereto as indicated at 48. An adjustable screw 49 threadedly disposed in an aperture 50 of the cover 12 is provided to vary the force in the spring to be applied to the lever 23 and, through it, to the roller 20.

Considering now the operation of this species of the invention, the strand or material to be formed is what is known as switchboard cable having a contour, after the assembling of the insulated electrical conductors in a sheath of selected materials, which is round or oval in cross

section. More specifically the switchboard cable may be either one of two forms; one, the normally round form and the other, normally oval form. The round form includes a group of insulated electrical conductors, their insulations being of a chosen group of color combinations, which after being brought together in a cable forming machine, are tied or bound together by a spiral textile wrapping, after which a double spiral wrapping of paper is applied. Over the paper, a spiral wrapping of metal foil is added and then another double spiral wrapping of paper, after which a longitudinal wrapping of a corrugated tape is applied and finally a braided covering of textile material. The cable in this condition is then passed through a bath of paint or other suitable material and after the cable has been allowed to dry, it is advanced between the rollers 14 and 20. In the other form of cable, shown in the drawing, the chosen group of electrical conductors with their insulated coverings of selected code colors are served spirally about a pressboard core which is a strip of flexible material approximately $1\frac{1}{4}$ " wide. The wires are secured to the core by spiral textile serving, after which a desired number of spiral servings of paper tape are applied, over which the longitudinal forming of the corrugated tape and the braided textile covering are applied. This cable is also passed through the paint bath and after drying it is in readiness to pass between the rollers 14 and 15. In either instance, it is desirable that the cable be reduced in thickness so that its space back of the switchboard will be no greater than the thickness of the jack strip to which its conductors are to be connected. These cables, therefore, serve to connect the terminals of the jack strips of one switchboard unit to the terminals of a similar jack strip of another switchboard unit. As the strand or cable, indicated at 52, is advanced between the guide members 53, it will be reduced in thickness, as illustrated in Fig. 2, to the chosen dimension. It is natural to assume that a cable of a given structure when reduced to a chosen thickness will have a given width as the material of the cable will flow laterally between the rollers to an overall width, depending first upon the quantity of material in the cable, and the distance of the rollers 14 and 20 from each other. Therefore, as the material or cable is formed as it advances between the fixed roller 14 and the roller 20, the latter, although variable in this instance, remains at a fixed position under normal conditions unless there should be an abnormal quantity of material at a portion in the strand of cable. When such a condition exists, the roller 20 may be moved with the lever 23 about the axis of the shaft 26 and against the force present in the spring 46 until the abnormal portion in the strand or cable has passed from between the rollers. When this condition occurs, the apparatus will automatically reset itself, the roller 20 returning to the selected position with respect to the roller 14 so that the remainder of the strand or cable will be reduced to the chosen dimension. There is no detrimental disturbance to the cable during its advancement between the rollers 14 and 20. During the initial forming of the cable, particularly the serving of the conductor wires spirally about the pressboard core, the resilient nature of the conductors will tend to cause them to project outwardly wherever possible to create an oval cross-sectional contour for the cable. The pressure applied to the cable will move these outwardly projecting portions of the

convolutions of the conductors in close proximity to the pressboard core and cause them to be set in this position without damaging the insulating coverings on the conductors or the layers of material surrounding the conductors.

If a different type of strand or cable is to be formed, the apparatus may be adjusted to vary the desired distance between the rollers 14 and 20 by rotating the dial 35 through the aid of the handle 39 until the selected indications on the dial have been moved into registration with the pointer 38. During this movement of the dial relative to the braking or holding means, the cam 30 in moving relative to the cam block 32 causes movement of the lever 23 about its pivot 26, and therefore varies the position of the roller 20 a measured distance indicated by the dial at the pointer from the roller 14. The apparatus is now in condition for operation, which operation may be performed in the same manner as previously described through the advancement of the material between the rollers.

The species of the invention shown in Figs. 4 and 5 is identical with that shown in Figs. 1, 2, and 3 with the exception of the handle 39 and the braking means including the plunger 41, the housing 42, and the other structure embodied therein. In place of the housing 40, a plate 60 is fixed to the adjacent side 11, by suitable means such as screws 61, and supports a pointer 62 positioned to register with indications 63 and 64 on a dial 65. The dial 65 is mounted upon a shaft 66 which supports a cam (not shown) identical with the cam 30. Associated with the cam, is a structure identical with that shown in Figs. 1 and 2. It will be understood therefore that variations in the position of the dial 65 with respect to its pointer 62 will cause variations in the position of a roller such as 20 with respect to a roller such as 14, for reducing the thickness of a strand or material to a given thickness and therefore to a given width.

The dial 65 is apertured at 67 to receive a member 68, the latter having an eccentrically disposed aperture 69 therein. A rod 70 is disposed in the aperture and is keyed in place as at 71 for axial movement in the aperture and for connection with the member so that rotation of the rod will cause rotation of the member in its aperture 67. A handle or gripping portion 72 is mounted upon the outer end of the rod 70 while the inner end has a reduced portion 73 receivable in any selected one of a multiplicity of grooves 74 in the plate 60. Through the aid of a spring 75, the rod 70 is normally urged to the right to force the end 73 into a selected one of the grooves 74. It is possible, however, to move the rod through the aid of the handle 72 to remove the end 73 from any groove 74 in which it is disposed. The grooves or recesses 74 are of like given widths substantially equal to the diameter of the end 73 and disposed radially about the shaft 66 so that their longitudinal center lines will lie in radial planes with the indications 63.

When a pointer 77 of a member 78, mounted upon the member 68, is at its zero (0) position (Fig. 5), dial with its associated mechanism may be moved to a selected indication 63 by pulling outwardly upon the handle 72 and through the aid of the handle moving the dial to the predetermined indication 63. By this adjustment, it will be known that the rollers are a given distance apart, which distance is the number of one hundredths of an inch as indicated by the dial at 75 the pointer. To obtain a finer adjustment, after

the selected main indication 63 has been positioned adjacent the pointer 62, the handle may be rotated to rotate the pointer 77 to register with any of the indications 80, that is, from the zero (0) to the nine (9) position to cause the member 68 to continue movement of the dial an additional distance and through a finer adjustment which is divided into $\frac{1}{1000}$ of an inch, to further vary the measured distance of the roller 20 from the roller 14. Thus, with this species of the invention, the same result may be accomplished as has been described in connection with the species shown in Figs. 1 to 3 inclusive, but with a finer adjustment of the position of the roller 20 with respect to the roller 14.

Although specific improvements of the invention have been shown and described, it will be understood that they are but illustrative and that various modifications may be made therein without departing from the scope and spirit of this invention as defined by the appended claims.

What is claimed is:

1. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller, whereby a strand advanced between the rollers will be reduced to a thickness equaling the distance between the rollers, and resilient means to normally urge the element to engage the cam.

2. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller, whereby a strand advanced between the rollers will be reduced to a thickness equaling the distance between the rollers, and resilient means to normally urge the element to engage the cam means to actuate the cam.

3. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller, whereby a strand advanced between the rollers will be reduced to a thickness equaling the distance between the rollers, a fixed pointer, and a dial movable with the cam and relative to the pointer to indicate the distance between the rollers.

4. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller whereby a strand advanced between the rollers will be reduced to a thickness equaling the distance between the rollers, a fixed pointer, a dial

movable with the cam and relative to the pointer to indicate the distance between the rollers, and means cooperating with the dial to hold the cam at any selected position relative to the element.

5. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller, whereby a strand advanced between the rollers will be reduced to a thickness equaling the distance between the rollers, and means to normally hold the element in engagement with the cam.

6. A strand forming apparatus comprising a main roller mounted for rotation upon a fixed axis, a companion roller, an element to support the companion roller, means to support the element for movement of the companion roller relative to the main roller, a cam actuable to move the element to move the companion roller to positions measured distances from the main roller, whereby a strand advanced between the rollers will be reduced to a thickness equaling the distances between the rollers, and variable resilient means to normally urge the element into engagement with the cam.

7. A strand forming apparatus comprising a main roller mounted for rotation upon a fixed axis, a companion roller mounted upon an axis movable relative to the said fixed axis, a pointer, a dial movable relative to the pointer to indicate in given fractional dimensions the distance between the rollers, means operable by the movement of the dial to control the position of the companion roller relative to the main roller, a handle to move the dial, and means under the control of the handle to latch the dial in any of a plurality of selected positions.

8. A strand forming apparatus comprising a main roller mounted for rotation upon a fixed axis, a companion roller mounted upon an axis movable relative to the said fixed axis, a pointer, a dial movable relative to the pointer to indicate in given fractional dimensions the distance between the rollers, means operable by the movement of the dial to control the position of the companion roller relative to the main roller, a handle to move the dial, means under the control of the handle to latch the dial in any of a plurality of selected positions, and means operable by movement of the handle relative to the dial to further vary the distance of the companion roller from the main roller for finer fractional dimensions.

9. A strand forming apparatus comprising a main roller mounted for rotation on a fixed axis, a companion roller, a support therefor movable relative to the said fixed axis, a variable stop to limit the movement of the support and the movable roller to predetermined variable positions relative to the main roller, and resilient means to normally urge the support toward and into engagement with the stop to force the companion roller into any selected one of the positions, whereby a strand advanced between the rollers will be reduced to a thickness equaling the distance between the rollers.

WALDEMAR C. EWALDSON.
